UNITED STATES PATENT OFFICE.

HENRY L. MENDAL, OF BALTIMORE, MARYLAND.

COOKER.

Application filed July 26, 1921. Serial No. 437,669.

To all whom it may concern:

Be it known that I, HENRY L. MENDAL, a citizen of the United States, residing at Baltimore, in the city of Baltimore and State of Maryland, have invented certain new and useful Improvements in a Cooker; and I do hereby declare the following to be a full, clear, and exact description of the invention, such as will enable others skilled in the art 10 to which it appertains to make and use the same.

The invention relates to a kitchen utensil of the type for preparing food and consists of a cooker to be placed upon any kind of 15 stove preferably a gas or oil stove and which is readily accessible and utilizes the heat to the best possible advantage.

Other objects and advantages will be apparent and suggest themselves as the nature 20 of the invention is understood.

While the drawing illustrates an embodiment of the invention it is to be understood that in adapting the same to meet different conditions and requirements, various changes 25 in the form, proportion and minor details of construction may be resorted to without departing from the nature of the invention.

Referring to the accompanying drawing forming a part of the specification,

30 Figure 1 is an elevation of a cooker embodying the invention showing the same mounted upon a gas stove and provided with a jacket.

Figure 2 is a sectional detail of the cooker, 35 the jacket being omitted.

Figure 3 is a horizontal section parts being broken away.

Figure 4 is a top plan view of the supporting frame, and

40 Figure 5 is a fragmentary view of the top portion of the drum showing more particularly the damper.

Corresponding and like parts are referred to in the following description and designated in the several views of the drawing by like reference characters.

The cooker comprises a drum 1 which is open at the bottom and closed at the top, the latter being provided with a centrally disposed damper 2 which is operable by means of a handle 3 projecting through a slot in the side of the drum. Openings are formed in opposite sides of the drum which are closed by doors 4 and 5 which are hinged 50 to swing in opposite directions. The drum 55 is provided with handles 1^a.

A supporting frame is disposed in the drum 1 and comprises uprights 6 and a cross piece 7, the latter being provided with a central opening for the escape of hot air 60 and vapor. The uprights 6 consist of plates which have their vertical edge portions outwardly deflected as indicated at 8 so as to make contact with the inner wall of the drum and the inner side of the doors as indicated 65 most clearly in Figure 3. In the preferable construction the uprights 6 and cross piece 7 may consist of a single strip of sheet metal having opposite end portions bent in the same direction to form the respective 70 parts. This supporting frame may be secured to the drum 1 in any preferred way.

A grate 9 is located within the lower portion of the drum and supports a bed 10 which preferably consists of soap stone of 75 suitable thickness and perforated to provide for the passage of the heat. The bed 10 is preferably of sectional formation, the sections being of like formation and of semi-circular form. The bed 10 acts as a deflector 80 to uniformly distribute the heat and prevent burning of the food in the process of cooking.

The supporting frame is designed to receive a receptacle containing the food to be 85 cooked. As shown most clearly in Figure 3 the receptacles 11 are of semi-cylindrical form so that each may receive a different article of food and when placed together economize space. Either receptacle 11 may 90 be removed or placed in position without disturbing the other because of the oppositely disposed doors 4 and 5. These doors when swung into open position entirely expose the supporting frame and admit of the receptacles 11 being easily placed in position or removed as required. A jacket 12 preferably encloses the drum 1 and serves to confine the heat. The handle 3 of the damper 2 projects through the slot in the side of the 100 jacket 12 near the top thereof as indicated most clearly in Figure 1. The jacket 12 is provided at opposite points with handles 13 for convenience of manipulating the cooker and handling the same. The cooker 105 is designed to be placed upon any type of heater or stove and the uprights 6 of the inner supporting frame provide passages at opposite sides for the circulation of hot air at the sides of the receptacles 11. The deflected edge portions 8 of the uprights 6 110 facilitate placing the cooking receptacles

11 in position since they give a flare to the space provided for the reception of the receptacles 11.

Having thus described the invention, what I claim is:—

1. A cooker comprising a drum, a supporting frame within the drum comprising an upper crosspiece and integral uprights, the latter having their vertical edge portions outwardly deflected and touching the inner wall of the drum to form opposite vertical channels.

2. A cooker comprising a drum having a centrally disposed damper in its top and a supporting frame within the drum comprising an upper crosspiece having an opening in register with the damper in the top of the drum, and integral uprights, the latter having their vertical edge portions outwardly deflected and in contact with the inner side of the drum to form opposed vertical channels.

3. A cooker comprising a drum open at the bottom and closed at the top and having a centrally disposed damper in the drum, a supporting frame within the drum compris-

ing uprights and an integral cross piece, the latter having a centrally disposed opening and the uprights having their vertical edge portions outwardly deflected, a grate in the lower portion of the supporting frame, and a sectional bed of refractory material such as soap stone mounted upon the grate and serving to equalize the heat.

4. A cooker comprising a drum having a damper in its top, a supporting frame within the drum comprising opposed uprights and a connecting cross piece, the drum having openings in opposite sides closed by means of doors, a grate at the lower portion of the supporting frame, a perforated bed of refractory material such as soap stone mounted upon the grate and a jacket enclosing the drum and having door controlled openings in its side opposite the doors of the drum.

In testimony whereof I affix my signature in presence of two witnesses.

HENRY L. MENDAL.
